CLAIM

The ornamental design for a targeting device, as shown and described.

DESCRIPTION

This patent or application file contains at least one drawing executed in color. Copies of this patent or patent application publication with color drawing(s) will be provided by the Office upon request and payment of the necessary fee.

FIG. 1 is a first, lateral perspective view of a targeting device in accordance with my new design;

FIG. 2 is a second, medial perspective view thereof;

FIG. 3 is first, anterior/posterior view thereof;

FIG. 4 is second, opposite anterior/posterior view thereof;

FIG. 5 is a medial view thereof;

FIG. 6 is a lateral view thereof;

FIG. 7 is a proximal view thereof; and,

FIG. 8 is a distal view thereof.
